Primary Examiner — Marissa J. Cash*Assistant Examiner* — Kayla Marie Bennett(74) *Attorney, Agent, or Firm* — Hawaii Patent Services;
Nathaniel K. Fedde; Kenton N. Fedde(57) **CLAIM**

The ornamental design for a flagpole bracket, as shown and described.

DESCRIPTION

FIG. 1 is a front, left, top perspective view of a flagpole bracket, showing my new design;

FIG. 2 is a rear, right, bottom perspective view thereof;

FIG. 3 is a front elevational view thereof;

FIG. 4 is a rear elevational view thereof;

FIG. 5 is a left side view of the enlarged scale thereof;

FIG. 6 is a right side view of the enlarged scale thereof;

FIG. 7 is a top plan view of the enlarged scale thereof;

FIG. 8 is a bottom plan view of the enlarged scale thereof;

FIG. 9 is an enlarged view of detail 1 in FIG. 9;

FIG. 10 is an enlarged view of detail 2 in FIG. 10;

FIG. 11 is an enlarged view of detail 3 in FIG. 11; and,

FIG. 12 is an enlarged view of detail 8 in FIG. 12.

The dashed broken lines in the figures illustrate portions of the flagpole bracket that form no part of the claimed design. The dash-dot-dash broken lines are for notating enlarged views and form no part of the claimed design.
